UNITED STATES PATENT OFFICE.

GEORGE FREDERICK STILLMAN, OF SYRACUSE, NEW YORK, ASSIGNOR TO THE SMITH PREMIER TYPEWRITER COMPANY, OF SYRACUSE, NEW YORK, A CORPORATION OF NEW YORK.

TYPE-WRITING MACHINE.

SPECIFICATION forming part of Letters Patent No. 739,623, dated September 22, 1903.

Application filed June 14, 1901. Serial No. 64,505. (No model.)

To all whom it may concern:

Be it known that I, GEORGE FREDERICK STILLMAN, a citizen of the United States, and a resident of Syracuse, in the county of Onondaga and State of New York, have invented 5 certain new and useful Improvements in Type-Writing Machines, of which the following is a specification.

This invention relates to type-bar bearings 10 of writing-machines; and its main object is to provide a simple and effective ball-bearing joint, but so thin that a large number of bars may be arranged in a limited space and guided accurately to the printing-center. Other ob- 15 jects will appear hereinafter.

My invention consists in certain combinations of devices, features of construction, and arrangements of parts, all as will be herein-after set forth, and particularly pointed out 20 in the concluding claims.

In the accompanying drawings, Figure 1 is a front view of a part of the type-bar system of a front-strike writing-machine, one type-bar being shown in printing position and another type-bar being shown in cross-section 25 in normal position. Fig. 2 is an enlarged side elevation of a type-bar mounted upon a segment, the latter being shown in cross-section. Fig. 3 is an enlarged sectional view showing 30 details of a hanger and a ball-spacer. Fig. 4 is an enlarged sectional edge view of a type-bar and hanger. Fig. 5 is a greatly-enlarged sectional edge view of the type-bar joint and illustrating the cupping of the type-bar plates, 35 which it is not possible to show in the other smaller views.

In the several views similar parts are designated by similar numerals of reference.

The blank for the type-bar is punched in 40 strip form from thin sheet metal and comprises widened heads or hub-plates 1 and shank portions 2, in which are formed laterally-projecting longitudinal U-section ribs 3. The strip or blank is folded transversely, so 45 as to bring the twin portions thereof together, and there is formed by the fold a hole or socket 4 to receive the stem of a type 5. The shank portions are secured together by a rivet 6 near the socket and by top and bottom riv-

ets 7 at the hub end of the bar. The shank 50 portions 2 abut throughout their length; but the hub portions or plates 1 are offset from the shanks, so as to form a fork.

The hub-plates 1 are pressed or stamped inwardly, so as to form upon their outer sides 55 circular depressions 8, which are centrally perforated to receive a short connecting-rivet or other fastener 9 and so as also to form upon their inner sides cones 10, which are arranged in opposition to each other and coöperate to 60 form a peripheral V-shaped groove-like ball-bearing.

The hanger or support for the type-bar comprises a disk 11, which is confined between the hub-plates 1 and provided with a central 65 perforation or eye 12, upon whose edge is formed an interior ball-bearing V-groove 13, which coöperates with the peripheral V-bearing in the type-bar hub to form a raceway for a series of balls 14, which are pref- 70 erably equally spaced by a notched separator 15, working upon the body of the rivet 9. In assembling the parts the type-bar, the hanger, the balls, and the separator are all arranged in the relationship shown, and then the shank 75 of the rivet is pressed through the perforations in the type-bar, hanger, and separator until its head comes to a bearing against the outer side of one of the cheek-plates of the type-bar. Then the projecting end of the 80 shank is spun or upset over the edge of the perforation in the other or opposite cheek-plate or hub until a sufficiently-tight fit of the balls in the raceway is obtained. By means of this construction the type-bar is 85 rigidly held against lateral vibration and at the same time is enabled to swing freely to the printing-point, while the width of the hub or bearing is reduced to a minimum, so that a large number of type-bars may be assem- 90 bled in a limited space. By pressing the hub-plates of the type-bars so as to form the desired peripheral ball-bearing surfaces or grooves the construction of the joint is greatly simplified, while owing to the springiness of 95 said hub-plates the hanger, the balls, and the separator may be readily introduced. Moreover, by forming a portion of the hub or

peripheral bearing upon each side portion of a cleft type-bar I am enabled to employ the inserted ball-spacer 15, which is a desideratum, as thereby the balls may be reduced in 5 number, preferably to the three.

In practice the rivet 9 is tightened enough to cause a slight cupping of the thin plates of the type-bar hub, the bearing portions of the cones being forced toward each other 10 slightly, and hence crowding the balls outwardly toward the base of the groove in the eye of the hanger. The purpose of producing this cupping or flexure of the hub-plates is to produce a spring tension of the plates, 15 whereby the cones are caused to tend constantly toward each other, so that wear of the joint may be automatically taken up as it occurs. If the joint should ever become too much worn to be compensated by such 20 spring or tension of the plates, the rivet 9 may be given a few blows by a hammer, so as to draw the plates closer together, thus both taking up the existing slack and also springing or cupping the plates anew, so as 25 to take up subsequent wear automatically. It will be understood that any other tightener may be employed in place of the rivet 9.

The base of the hanger, which is designated as 16, is united to the disk or eye portion 11 30 thereof by an arm or neck 17, which is curved or recessed at 18 to form a clearance for the head of a link 19, whose forward end is connected to a key-operated lever. (Not shown.) The hanger-bases 16 are inserted in slots 20, 35 cut radially in a segment 21. The latter is provided with a cover-plate 22, permanently fastened by rivets 23. The hangers are inserted endwise into the rectangular apertures formed by the coöperation of the slots with 40 the cover-plate and are retained by set-screws 24, tapped into the latter and bearing against the front edges of the hangers, which fit snugly in the slots and are adjustable radially therein. It will be seen that the interiorly-grooved eye in the hanger is embraced by the cleft hub portion of the type-bar; that 45 opposing cones are formed integrally upon the type-bar and connected by the rivet 9; that a series of bearing-balls runs in the race 50 formed by the coöperation of said cones with said interior groove; that the eye portion of the hanger surrounds the cones of the type-bar; that the type-bar is formed of opposing plates, preferably formed in one piece, the 55 fold being preferably at the type-bearing end of the type-bar; that the sides of the type-bar are springy, and hence may be drawn together by the rivet 9 or other suitable device until the requisite fit of the joint is secured; 60 that the hub-plates of the type-bar are preferably offset from the shank portions, the purpose of offsetting them being to separate the hub-plates, so as to permit the introduction of the hanger; that the type-bar comprises 65 contiguous twin plates secured together and having at one end a type-socket and at the other end cones pressed in the

metal of the type-bar, so as to form a ball-groove, and that the transverse connector 9 is arranged centrally or at the axes of the 70 cones.

Various changes in design and details of construction may be made without departing from the spirit of my invention.

It will likewise be seen that the depressions 8, formed by striking up the cones 10 in the hub-plates, provide recesses in which the heads of the rivets or fastenings 9 are contained, so that the length of each fastening may be made even less than the width of its 80 type-bar at the point of connection with the hanger, and that each type-bar has two circular oppositely-arranged cup-like portions with oppositely-flaring rims or flanges 10, that form a V-shaped ball-bearing raceway around 85 the webs or body portions of said cups, and that the cups or cones are adapted to be flexed to maintain a pressure on the bearing-balls to automatically compensate for wear upon 90 the parts.

What I claim as new, and desire to secure by Letters Patent, is—

1. The combination of a hanger, a type-bar, one of said members being formed of sheet metal and comprising two circular oppositely-arranged cup-like portions having oppositely-flaring rims or flanges to form a raceway 95 around the webs or body portions of said cups, a transverse fastening uniting said webs or body portions and the other one of said members having an internally-grooved eye portion surrounding said cup-like portions and a set of bearing-balls.

2. The combination of a hanger, a type-bar, one of said parts being formed of folded sheet 105 metal having pressed therein opposing cup-like cones, and the other of said parts having an interiorly-grooved eye portion surrounding said cones, a set of bearing-balls, and a transverse fastener for said cones.

3. The combination of a hanger and a type-bar, one of said parts being formed of opposing plates and said plates having pressed therein opposing cup-like cones, and the other of said parts having an interiorly-grooved eye 115 portion surrounding said cones, a set of bearing-balls, and a transverse fastener whose ends or heads are seated in the depressed portions of the cup-like cones.

4. The combination of a hanger, a type-bar, one of said parts having springy sides and 120 said sides having pressed therein opposing cones, and the other of said parts having an interiorly-grooved eye portion surrounding said cones, a set of bearing-balls, and a transverse fastener which is caused to draw said cones together and place them under spring 125 tension so as to produce the requisite fit of the joint and compensate for wear upon the parts.

5. The combination of a hanger, a type-bar, one of said parts having springy sides and 130 said sides having pressed therein opposing cones and also being provided with perfora-

tions, and the other of said parts having an interiorly-grooved eye portion surrounding said cones, a set of bearing-balls, and a rivet, one of whose heads is drawn or spun over the 5 edge of a perforation so as to draw the cones together and place them under spring tension which is exerted on the bearing-balls and produce the requisite fit of the joint.

6. The combination of a hanger having an 10 interiorly-grooved eye, a type-bar having at one end a type-socket and at the other end a cleft hub portion provided with opposing thin sheet-metal cup-like cones which are surrounded by said eye, means for connecting 15 said cones, and a set of bearing-balls.

7. The combination of a hanger having an 20 eye provided with an interior groove, a cleft type-bar embracing the eye, opposing cones formed integrally upon the cleft portion of the type-bar, means for connecting the cones, and a series of bearing-balls running in the race formed by the coöperation of said cones with said interior groove.

8. The combination of a type-bar formed 25 of folded sheet metal and having offset hub-plates in which are pressed opposing cup-like cones, a hanger having an interiorly-grooved eye portion surrounding said cones, a set of bearing-balls, and a transverse fastener for 30 said cones.

9. The combination of a type-bar formed 35 from a transversely-folded strip and having a type-socket formed by the fold, opposing cup-like cones being pressed in the hub portions of the type-bar, a hanger having an interiorly-grooved eye portion surrounding said cones, a set of bearing-balls, and means for connecting the cones.

10. The combination of a type-bar having 40 a cleft springy hub portion in which are pressed opposing cup-like cones, a hanger having an interiorly-grooved eye portion surrounding said cones, a set of bearing-balls, and a transverse fastener which is caused to 45 draw said cones together so as to produce the requisite fit of the joint.

11. A type-bar formed from a sheet-metal strip transversely folded and having a type-socket formed by the fold, the shank portions 50 of the strip abutting and the ends of the strip being offset so as to form separate hub-plates, and said plates being formed with circular depressions 8 and outwardly-flaring circular ball-bearings 10 and having a transverse connector.

12. A type-bar formed from folded sheet metal and having offset hub-plates, which are formed with circular depressions 8 and outwardly-flaring circular ball-bearings 10.

13. A type-bar comprising contiguous twin 60 plates secured together and having at one end a type-socket and at the other end circular depressions 8 and outwardly-flaring circular ball-bearings 10, the portions 8 being arranged close together and riveted centrally of the length of the type-bar and the portions 10

extending outwardly therefrom on opposite sides.

14. A blank for a folded type-bar consisting of hub-plates at the ends thereof, ribbed shanks, and a socket portion, said hub-plates being offset from the shanks and having two reversely-arranged cup-like portions with outwardly-flaring circular ball-bearing surfaces.

15. The combination of a hanger, a type-bar, one of said members having an eye provided with an interior groove and the other of said members being cleft and embracing the eye, opposing cup-like flexible cones formed integrally upon said cleft member, a central transverse connector for said cones, a series of bearing-balls running in the race formed by the coöperation of said cones with said interior groove, and a ball-spacer mounted upon said connector.

16. The combination of a sheet-metal type-bar having pressed in its sides a pair of opposing cup-like ball-bearing cones, a central connector for said cones, a hanger having an interiorly-grooved eye surrounding said cones, a set of bearing-balls, a ball-spacer mounted upon said connector.

17. The combination of a hanger and type-bar, one of said parts being formed of sheet metal and having opposing cones, and the other of said parts having an interiorly-grooved eye portion surrounding said cones, a set of bearing-balls, and a device for causing said cones to spring toward each other so as to take up automatically the wear of the joint.

18. The combination of a hanger and a type-bar, one of said parts being formed of thin sheet metal and having pressed therein opposing cones, and the other of said parts having an interiorly-grooved eye portion surrounding said cones, a set of bearing-balls, and a transverse device arranged axially of said cones and serving to cup or spring said cones toward each other.

19. The combination of a hanger and type-bar, one of said parts being formed of sheet metal and having opposing cones and the other of said parts having an interiorly-grooved eye portion surrounding said cones, and a set of bearing-balls; the said opposing cones having a normal spring tension toward each other and acting to force the balls outwardly toward the base of the groove in the surrounding eye portion and so that should wear occur said cones may under the said tension automatically approach each other so as to compensate for said wear.

20. The combination of a hanger and type-bar, one of said parts being formed of sheet metal and having opposing cones and the other of said parts having an interiorly-grooved eye portion surrounding said cones, an intermediate set of bearing-balls, and means for imparting to said cones a spring tension toward each other after the assemblage of the parts, whereby said cones may

automatically approach each other and take up any wear in the balls or bearings that may subsequently occur during use.

21. The combination of a hanger having an interiorly-grooved eye portion, a sheet-metal type-bar having opposing cones formed integrally therewith, a set of balls arranged to bear on said cones and in said grooved eye portion, and a transverse rivet adapted, after 10 assemblage of the parts, to cause the said

cones to have a normal spring tension toward each other so as to enable them automatically to approach each other when wear occurs.

Signed at Syracuse, in the county of Onondaga and State of New York, this 8th day of 15 June, A. D. 1901.

GEORGE FREDERICK STILLMAN.
